UNITED STATES PATENT OFFICE.

WILLIAM J. COLLINS, OF BROOKLYN, NEW YORK.

GRINDING MACHINE.

1,418,235.

Specification of Letters Patent. Patented May 30, 1922.

Application filed May 21, 1921. Serial No. 471,385.

To all whom it may concern:

Be it known that I, WILLIAM J. COLLINS, a citizen of the United States, and a resident of the city of New York, borough of Brooklyn, in the county of Kings and State of New York, have invented a new and Improved Grinding Machine, of which the following is a full, clear, and exact description.

The present invention relates to new and useful improvements in grinding machines, and it pertains more particularly to a machine especially adapted for the grinding of valves of internal combustion motors.

It is one of the objects of the invention to provide in combination with a grinding element, means for supporting the valve to be ground in grinding contact with said grinding element.

It is another object of the invention to provide means whereby the valve to be ground may be adjusted relatively to the grinding element in order that seats of various angles may be ground upon the valve.

It is a further object of the invention to provide means whereby the valve and the valve seat of an internal combustion motor or similar machine may be ground by use of the same device and have contacting seats of different angles.

It is a further object of the invention to provide means whereby the valve being ground may be moved in opposite directions across the grinding element in contact therewith at the will of the operator.

It is a still further object of the invention to provide means in combination with the feeding means of the valve to constantly rotate the valve during the grinding operation.

With the above and other objects in view, reference is had to the accompanying drawings, in which—

Figure 1 is a view in side elevation of a machine constructed in accordance with the present invention;

Fig. 2 is a top plan view;

Fig. 3 is a detail sectional view taken on the line 3—3 of Fig. 2;

Fig. 4 is a detail view in elevation of the traveling carriage of the machine;

Fig. 5 is a detail sectional view taken on the line 5—5 of Fig. 1;

Fig. 6 is a detail sectional view taken on the line 6—6 of Fig. 4.

Referring more particularly to the drawings, the machine comprises a base 10 se-

cured to a bench or other suitable support by means of screws, bolts, or the like 11, passing through feet 12 formed on said base. The base is provided with a plurality of spaced lugs 13, and mounted in said lugs are guide rods 14. Suitably mounted on these guide rods 14 is a carriage or table 15, and depending from said table 15 is a pair of spaced lugs 16, extending downwardly between the sides of the base 10. In order to provide for slidably mounting the table 15 on the guide rods 14, the table is provided at diametrically opposite points with guides or the like 17 through which the rods 14 pass.

Referring to Fig. 3 it will be apparent that the table 15 is hollowed out as indicated by the reference character 18, and mounted in said hollowed out portion 18 is a bevel gear 19. This bevel gear 19 is carried upon a vertical shaft 20 mounted in a bearing 21 in the table 15, and carried upon the lower end of said shaft 20, is a bevel gear 22.

The forward end of the base 10 is provided with a lug 25, and said lug 25 is internally screw-threaded. Passing through the lug 25 and having threaded engagement therewith, is a shaft 26, said shaft being threaded as indicated by the reference character 27. The outer end of this shaft 26 is squared as at 28 to provide for the attachment of an operating handle 29.

The reference character 30 designates a bevel gear mounted upon the shaft 26, and this bevel gear 30 meshes with the bevel gear 22 on the lower end of the shaft 20. As more clearly shown in Fig. 5, the bevel gear 30 is rigidly carried by a sleeve 31 and said sleeve is adapted to be secured to the shaft 26 by means of a set screw 27a. When this set screw 27 is loosened, the shaft 26 is free to rotate within the sleeve 31 for a purpose to be hereinafter more specifically described. This sleeve 31 heretofore mentioned is mounted between the depending lugs 16 of the table 15 and the shaft 26 is extended beyond said lugs and mounted in a transverse partition or brace 34.

By this construction it is apparent that as the shaft 26 is rotated by means of the operating handle 29, the shaft will move longitudinally of the threaded lug 25 and that in so moving owing to the fact that the sleeve 31 is mounted between the lugs 16, the table 15 will be moved longitudinally

of the guide rods 14. Simultaneously with this movement through the medium of the bevel gears 30 and 22 and the shaft 20, the bevel gear 19 will be rotated.

5 Mounted upon the table 15 is a platform 40, and carried by said platform 40 is a bearing or the like 41. This platform 40 is adapted to be rotatably mounted upon the table 15 and the same is maintained 10 against rotation relative to the table by means of a dog 42. The construction of this locking means is shown in Fig. 6, and in said figure it will be seen that the platform 40 is provided with an annular angular 15 lar groove 43 with which the dog 42 is adapted to engage. In order to cause engagement of the dog 42 with the angular groove 43, a screw-threaded plug 44 provided with a socket 45 for the reception of 20 a wrench, is mounted in the table 15. By this construction it will be apparent that as the plug 44 is turned up, the dog 42 will be forced into engagement with the groove to prevent movement of the platform 40 25 relative to the table 15. To permit of rotary movement of the platform 40, it is only necessary to back the plug 44 out of its recess and out of engagement with the dog 42. This action provides a space at the 30 forward portion of the recess into which the dog 42 is free to move upon rotary movement of the platform 40. As the dog 42 moves into this space the platform is free to rotate since the dog has been disengaged from the angular-groove.

35 Mounted in the bearing 41 heretofore mentioned, is a chuck and said chuck comprises an inner resilient member 47 screw-threaded as at 48 and engaged by a sleeve 49, said sleeve being screw-threaded as at 50. The outer end of the sleeve is squared as at 51, to provide means by which it may be engaged by a wrench to rotate the sleeve 49 and cause a retraction of the resilient member 47 to grip about the stem of a valve 52. Surrounding the sleeve 49 is a sleeve 53, and carried by the sleeve 53 is a bevel gear 54, which meshes with the bevel gear 19. By this construction it will be seen 50 that as the bevel gear 19 is rotated, the sleeve 51 will be rotated through the medium of the gear 54 and the valve 52 carried by the resilient member 47 of the chuck will likewise be rotated.

55 Mounted in a lug 56 upon the top of the bearing 41, is a sliding member 57, which is adapted to engage the teeth of the bevel gear 54 under the influence of the coil spring 58 when the pin 59 has been 60 removed, the lower end of said pin 59 engaging in a recess in the lug 56.

From the foregoing construction it is apparent that the valve 52 carried by the chuck in addition to being rotatably mounted, is capable of movement relative to the

base 10, to move the valve across the face of the grinding wheel 77.

65 The sliding member 57 is provided with a pawl 60 which is adapted to engage between the teeth of the gear 54 to prevent 70 rotation of said gear in order that the member 49 may be prevented from rotating when the end 51 thereof is engaged by a wrench to operate the chuck to adjust and remove the valve therefrom.

75 Upon the opposite end of the base 10, a plurality of lugs 70 are formed and slidably mounted in said lugs 70 are guide rods 71. These guide rods 71 support a table or base 72, and mounted upon said base 72 is a motor 80 73. This base 72 is provided with threaded depending lugs 74 and engaging therewith is a threaded shaft 75 operated by a handle 76. By this construction it is apparent that upon rotation of the handle 76, the motor 85 73 will be moved transversely of the base 10, owing to the threaded engagement of the shaft 75 with the threaded lugs 74. The armature shaft 76' of the motor 73 extends parallel to the longitudinal axis of the base 90 of the machine, and the inner end of this shaft 76' is provided with a grinding wheel 77 and said grinding wheel will be moved transversely of the machine upon movement of the motor transversely of the machine in the manner hereinafter described.

95 The device operates in the following manner:

100 The valve 51 is positioned within the chuck in the above-described manner, after which the screw-threaded plug 44 is backed out of its screw-threaded recess to permit of 105 rotary movement of the platform 40 relative to the table 15. When this platform 40 has been properly adjusted, which adjustment will be indicated by the scale 100 shown in Fig. 4, the screw-threaded plug 45 is forced inwardly of its recess and the dog 42 engaged with the annular groove 43 in 110 the platform 40. By this means it is apparent that the proper angular adjustment of the valve 52 relative to the grinding wheel 77 is had. The motor 73 is now started and the grinding wheel 77 is rotated. Upon grasping the operating handle 29 and 115 rotating the same, the table 15 will be moved longitudinally of the guide rods 14 in the manner heretofore described and the valve 42 will be advanced in the direction of the grinding wheel 77. When the valve has advanced far enough to intersect the path of travel of the grinding wheel transversely of the machine, the operating handle or lever 76 is rotated to move the motor 73 and grinding wheel 77 into contact with the valve 120 52. As the grinding wheel 77 contacts with the valve 52, the grinding operation starts and a face is ground upon the valve 52.

125 In order that the valve may be ground to the proper extent, it is only necessary to 130

rotate the operating handle 29 in opposite directions to move the valve across the grinding face of the grinding member 77 and from time to time move the operating handle 76 in order that the motor may be kept in the proper position to engage at all times the face being ground upon the valve.

In addition to grinding valves, the device is adapted to grind tools, and more particularly reamers for resurfacing valve seats with which the valves are subsequently adapted to engage. In carrying out this operation, assuming that the face on the valve 52 has been cut to an angle of thirty-five degrees, the reamer with which it is intended to resurface a seat will be engaged in the chuck in the same manner as is the valve 52, and the platform 40 will be adjusted relatively to the table 15 in such a position that the several teeth of the reamer will be positioned at an angle of thirty-five degrees relative to the grinding wheel 77. After the work has thus been positioned or set, the pawl 60 in the sliding member 57 is engaged with the teeth of the gear 54 to prevent rotation thereof and the screw 27 loosened, it being understood, of course, that the grinding wheel and the teeth of the reamer have been engaged in such a manner that when the motor is started, the teeth of the reamer will be ground to thirty-five degrees. It is further to be understood that the several teeth of the reamer will be ground separately.

From the foregoing it is apparent that when the reamer is ground, the teeth or cutting edges thereof will correspond to the angle of the face of the valve and when the seat with which the valve is adapted to engage has been faced by said reamer, the angle of the face of the valve and the seat with which it is adapted to engage will coincide.

From the foregoing it is apparent that the present invention provides a new and improved machine for use particularly in connection with the grinding of valves of internal combustion motors, pumps and the like, and that said machine is particularly useful for obtaining accurate results without the employment of large machines, such as turret lathes, turret grinders and the like.

I claim:

1. A valve grinding device comprising a base, a table movable longitudinally of said base, a valve holder carried by said table, a train of gearing for rotating said valve holder, means for driving said train of gearing, means for engagement with one of the gears of said train of gearing for locking the same against operation, and means for releasing another of the gears of said train of gearing to permit the driving member of the train of gearing to rotate without driving said train of gearing. 65

2. In a valve grinding machine, a base having a screw threaded opening, a rotatable rod mounted in said base and engaging said screw-threaded opening, whereby upon rotation of the rod it will be moved relative to the base, a table movable with respect to said base, means carried by the table and having engagement with said rod whereby upon rotation of said rod the table will be moved relative to the base, a valve holder, 75 a train of gears for rotating said valve holder, one of the gears of said train of gears being carried by said screw-threaded rod, means for releasably securing said gear to the rod to cause the gear to rotate there-with, and means for engaging one of the gears of said train of gearing to lock the train of gearing against rotation. 80

3. In a valve grinding machine, a base having a screw-threaded opening, a screw-threaded rod having engagement with said screw-threaded opening and rotatably mounted in the base, a table movable relatively to the base, a plurality of lugs depending from said table and means on said rod engaging said lugs whereby upon rotary movement of the rod the table will be moved relatively to the base, a valve holder carried by said table, a train of gearing for rotating said valve holder, said train of gearing being operated from a gear carried by said rod, means for engaging one of the gears of said train of gearing to prevent operation of the train of gearing, and means for releasing the driving gear from the screw-threaded rod when the driving train is locked against operation. 95

WILLIAM J. COLLINS.
